(57) CLAIM

The ornamental design for a capsule for making beverages, as shown and described.

DESCRIPTION

FIG. 1 is a front perspective view of a capsule for making beverages;

FIG. 2 is a side elevational view, with the view being the same 360° around the capsule thereof;

FIG. 3 is a top elevational view thereof; and,

FIG. 4 is a bottom elevational view thereof.

CERTIFICATE OF CORRECTION

PATENT NO. : D742,221 S
APPLICATION NO. : 29/464107
DATED : November 3, 2015
INVENTOR(S) : Franco Casiddu

It is certified that error appears in the above-identified patent and that said Letters Patent is hereby corrected as shown below:

Delete title page and substitute therefore with the attached title page consisting of the corrected illustrative figures.

Delete Drawing Sheets 1-4 and substitute therefore the attached Drawing Sheets 1-4. FIGS. 1-4 have been corrected.

Signed and Sealed this
Twenty-third Day of February, 2016

Michelle K. Lee
Director of the United States Patent and Trademark Office
